(57) **CLAIM**

The ornamental design for an electric connector, as shown and described.

DESCRIPTION

FIG. 1 is a front elevational view of an electric connector showing my new design;

FIG. 2 is a top plan view thereof;

FIG. 3 is a rear elevational view thereof;

FIG. 4 is a bottom plan view thereof;

FIG. 5 is a right side elevational view thereof on a larger scale;

FIG. 6 is a left side elevational view thereof on a larger scale;

FIG. 7 is an enlarged cross-sectional view taken along line 7—7 in FIG. 1;

FIG. 8 is an enlarged cross-sectional view taken along line 8—8 in FIG. 1;

FIG. 9 is a front, top, and right side perspective view thereof;

FIG. 10 is a front, bottom, and right side perspective view thereof;

FIG. 11 is a front, top, and right side perspective view thereof, in a use condition coupled with cables for signal transmission;

FIG. 12 is a front, bottom, and right side perspective view thereof, in a use condition; and,

FIG. 13 is a front, top, and right side perspective view thereof, in a use condition.

The broken lines in the drawings depict environmental subject matter only and form no part of the claimed design.
